(57) CLAIM

The ornamental design for a hand rake, as shown and described.

DESCRIPTION

FIG. 1 is a perspective view of a rake showing my design;
FIG. 2 is a front view thereof;
FIG. 3 is a back view of FIG. 2;
FIG. 4 is a right side view thereof;
FIG. 5 is a left side view thereof;
FIG. 6 is a top view thereof; and,
FIG. 7 is a bottom view thereof.

The broken lines represent portions of the article and form no part of the claimed design.

1 Claim, 6 Drawing Sheets

FIG. 2

FIG. 3

FIG. 4

FIG. 5
